(57) **CLAIM**

The ornamental design for a bottle, as shown and described.

DESCRIPTION

FIG. 1 is a top, front, left perspective view of a bottle showing our new design;

FIG. 2 is a top, right, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is an enlarged, partial, top, front, left perspective view thereof.

The dashed broken lines show portions of the bottle that form no part of the claimed design. The dot-dash broken lines show claim boundaries that form no part of the claimed design.
